US00D804510S

(12) **United States Design Patent** (10) **Patent No.:** **US D804,510 S**
Federighi et al. (45) **Date of Patent:** **** Dec. 5, 2017**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Craig M. Federighi**, Los Altos Hills, CA (US); **Christopher Foss**, San Francisco, CA (US); **Woo-Ram Lee**, Sunnyvale, CA (US); **Stephen O. Lemay**, San Francisco, CA (US); **Caelan G. Stack**, San Francisco, CA (US); **Lawrence Yang**, San Francisco, CA (US)

(73) Assignee: **Apple Inc.**, Cupertino, CA (US)

(**) Term: **15 Years**

(21) Appl. No.: **29/599,048**

(22) Filed: **Mar. 30, 2017**

Related U.S. Application Data

(63) Continuation of application No. 29/573,056, filed on Aug. 2, 2016, now Pat. No. Des. 787,545, which is a continuation of application No. 29/529,430, filed on Jun. 7, 2015, now Pat. No. Des. 765,700.

(57) **CLAIM**

The ornamental design for a display screen or portion thereof with graphical user interface, as shown and described.

DESCRIPTION

FIG. 1 shows a display screen or portion thereof with graphical user interface showing our new design; and, FIG. 2 shows a second embodiment thereof.

The peripheral dashed broken lines illustrate a display screen or portion thereof and form no part of the claimed design.

The dashed broken lines within the peripheral dashed broken lines illustrate portions of the graphical user interface which form no part of the claimed design.

1 Claim, 2 Drawing Sheets
